PUMP OR COMPRESSOR

Omar E. Clark, Highland Park, Mich.

Application October 4, 1940, Serial No. 359,629

14 Claims. (Cl. 103—161)

This invention relates to variable pressure variable capacity pumps wherein the fluid volume delivered varies inversely proportional to the delivery pressure.

In many hydraulic installations, such as hydraulic riveters, hydraulic presses and the like, the pressure required to perform the desired operation varies during the performance of the said operation. In such installations, the operation performed can be performed more rapidly and effectively by employing a pump which will deliver a high volume at a low pressure and change automatically and instantaneously to a relatively lower delivery volume at a relatively higher pressure or vice versa responsive to any change of pressure against which the pump operates.

With the foregoing in view, the primary object of the invention is to provide a hydraulic pump adapted to deliver a variable volume of fluid at a pressure which varies inversely proportional to the volume delivered wherein the said volume of fluid delivered is variable automatically responsive to the pressure against which the pump operates.

Another object of the invention is to provide a hydraulic pump in which the stroke of its pistons and volume of fluid delivered vary automatically and instantaneously from a predetermined minimum to a predetermined maximum responsive to the pressure against which the pump operates and including means for regulating the pressure at which the stroke of the pump pistons and the volume of fluid delivered thereby vary.

Another object of the invention is to provide a simple, inexpensive-to-manufacture hydraulic pump having an automatically variable delivered volume and delivery pressure and wherein the delivered volume is inversely proportional to the delivery pressure, the said pump requiring a constant horsepower to operate regardless of the pressure against which it operates within the limits of its capacity.

Other objects of the invention will become apparent by reference to the following detailed description taken in connection with the accompanying drawings, in which:

Fig. 1 is a vertical sectional view of a four-cylinder pump embodying the invention taken on the line 1—1 of Fig. 2.

Fig. 2 is a longitudinal sectional view of the pump disclosed in Fig. 1 taken on the line 2—2 thereof looking in the direction indicated by the arrows.

Fig. 3 is a fragmentary longitudinal sectional view of the adjusting sleeve employed to adjust the torsional pump pressure regulating spring anchored to the main shaft and to the eccentric shaft.

Fig. 4 is a cross sectional view taken on the line 4—4 of Fig. 3.

Fig. 5 is a cross sectional view taken on the line 5—5 of Fig. 2 showing a preferred construction of the anchorage of the torsional pump pressure regulating spring to the eccentric shaft.

Fig. 6 is a detailed sectional view taken on the line 6—6 of Fig. 1 showing intake and exhaust valve mechanism preferably employed for each cylinder.

Fig. 7 is a vertical sectional view taken on the line 7—7 of Fig. 2 showing wrench means employed to adjust the torsional spring pressure between the main and eccentric shafts.

Fig. 8 is a rear elevational view of the pump showing the suction and discharge conduit system preferably employed.

Fig. 9 is a side elevational view of the pump also showing the suction and discharge conduit system employed.

Although the illustrative embodiment of the invention disclosed in the drawings and described in detail has four cylinders, obviously, the invention may be practiced in 4, 6, 8 or more cylinder embodiments or with any reasonable and practical number of cylinders; the drawings and description herein being intended to be illustrative and not limiting in this and other respects.

Referring now to the drawings wherein like numerals refer to like and corresponding parts throughout the several views, the illustrative embodiment of the invention disclosed comprises, in general, a main pump casting 10 having four radially disposed cylinders 11 formed therein 20 into which are reciprocatingly mounted pistons 12, three of which are connected by connecting rods 13 to a master connecting rod hub 140 of the master connecting rod 14 connected to the other or fourth piston 12, the said master connecting rod hub 140 being mounted on a master wrist pin 15 preferably formed integral with and eccentric to an eccentric shaft 16 mounted for turning approximately 180 degrees axially within a main shaft 17 on a needle bearing 18 at one end and the sleeve bearing 19 at the other end. The said main shaft 17 is mounted for rotation on ball bearings 20 and 21 within a housing 22 secured to the main pump body casting 10 by suitable socket head studs 23. A counterweight 24 is keyed on the forwardly extending end of

the master wrist pin 15 and is of suitable weight and proportions to maintain dynamic balance of the moving parts of the pump. A torsional pump pressure regulating spring 25 is anchored at one end to the eccentric shaft 16 by means of a spring anchor arm 26 and is anchored at its other end to the main shaft 17 by means of a pump pressure regulating spring adjustment collar 27 as hereinafter described in detail. Each cylinder 11 is provided with an intake valve 28 and a discharge valve 29 preferably as indicated in Fig. 6.

The main pump casting 10 preferably has a base 100 an intake conduit 30 formed along the top and bottom thereof communicating with the intake valves 28 and preferably has a discharge conduit 31 formed along each side thereof communicating with the discharge valves 29. The intake conduits 30 in the top and bottom of the main pump casting 10 are preferably connected together by a bent flared end tubing 33. One of the intake conduits 30 and one of the discharge conduits 31 in the main pump casting 10 are each provided with suitably threaded female intake and discharge line connecting fittings 34 and 35 respectively integrally cast with the main pump casting 10 as best shown in Figs. 1 and 8. Figs. 1, 2, 6, 8 and 9 show clearly the conduit and valve system preferably employed in the illustrative embodiment of the invention disclosed in the drawings. Where it has been necessary to bore the main pump casting 10 to form cylinders, valve compartments, valve ports, and the like, the casting 10 has been plugged by employing suitable flanged socket head plugs 36 and washers 37 or taper threaded socket plugs 38.

The said cylinders 11 formed in the main casting 10 are preferably provided with suitable liners 39 as indicated in Figs. 1 and 2. The connecting rods 13 are connected to the master connecting rod hub 140 by suitable wrist pins 40 and to the pistons 12 by a ball and socket connection generally designated by the numeral 41 throughout the drawings. The master connecting rod 14 is rigidly connected at its inner end to its hub 140 by such means as the socket head studs 42 and is connected at its outer end to a piston 12 by means of a ball and socket connection 41. The employment of ball and socket connections 41 between the pistons 12 and connecting rods 13 and 14 compensates for any slight misalignment which may occur during manufacture and assembly.

The center B of the master wrist pin 15 formed integral with and eccentric to the eccentric shaft 16 is permitted to turn 180 degrees in the direction indicated by the dotted line arrow 43 in Figs. 1 and 5 around the center A of the main shaft 17 until the center B of the master wrist pin 15 takes the position indicated by the letter C. While the eccentric shaft 16 is turning within the main shaft 17, the said center B of the master wrist pin 15 follows a path indicated by the dot and dash line 80 as shown in Figs. 1 and 5.

The said turning movement of the master wrist pin 15 is permitted by the winding of the torsional pump pressure regulating spring 25 responsive to the pressure against which the pump operates which induces a torque between the eccentric shaft 16 and the main shaft 17 when the main shaft 17 is rotated in the direction indicated by the full line arrow 44 shown in Figs. 1 and 5 by suitable power means applied to its extended end 170. When the pump is not operating or operating under a pressure less than required

5 to develop sufficient torque between the eccentric shaft 16 and the main shaft 17 to wind the torsional pump pressure regulating spring 25, the eccentric shaft 16 takes its low pressure high volume operating position with respect to the main shaft 17 indicated in Figs. 1 and 5. In the low pressure high volume operating position of the eccentric shaft 16, the eccentricity of the center B of the master wrist pin 15 thereof with respect to the center A of the main shaft 17 is maximum. The eccentric shaft 16 and the torsional pump pressure regulating spring anchor arm 26 extending radially outward from the center D of the said eccentric shaft 16 and disposed in a semicircular slot 45 in the main shaft 17 are urged by the said torsional pump pressure regulating spring clockwise as viewed in Fig. 1 and counterclockwise as viewed in Fig. 5 until the said spring anchor arm 26 rests against the shoulder or radial face 46 thereof.

10 As the pressure against which the pump operates increases from a relatively low pressure to a relatively high pressure, the torque between the eccentric shaft 16 and the main shaft 17 increases until it begins to wind the torsional pump pressure regulating spring 25 whereupon the said eccentric shaft 16 begins to turn about its center D in the direction indicated by the dotted line arrow 43 in Figs. 1 and 5 and the said anchor arm 26 moves from the radial shoulder or face 46 of the main shaft 17 toward the radial shoulder or face 460 of the main shaft 17 located 180 degrees counter to the rotation of the main shaft 17 from the said radial shoulder or face 46. When the said pressure against which the pump operates becomes maximum, the eccentric shaft 16 completes its 180 degree turning movement and the said pump pressure regulating spring anchor arm 26 comes to rest against the said shoulder or face 460 of the main shaft 17 as indicated by the dotted line showing of the anchor arm 26 and hooked end 47 of the torsional spring 25 in Fig. 5.

15 During the turning of the said eccentric shaft 16 about its center D while the pressure against which the pump is operating increases from a minimum to a maximum, the eccentricity of the center B of the master wrist pin 15 with respect to the center A of the main shaft 17 decreases in inverse proportion to the said pressure against which the said pump operates until the said center B of the said master wrist pin 15 reaches the point C whereat the eccentricity thereof is at a minimum with respect to the center A of the said main shaft 17. Therefore, it is obvious that the reducing of the eccentricity of the eccentric shaft 16 and the center of the master wrist pin 15 with respect to the center of the main shaft 17 responsive to the increase of pressure against which the pump operates varies the stroke of the pistons 12 with a corresponding variation in volume delivered and the volume delivered by the pump varies inversely proportional to the pressure against which the pump operates and vice versa.

20 The torsional pump pressure regulating spring 25 is anchored at one end to the eccentric shaft 16 by hooking the end 47 thereof over the outer grooved end 48 of the spring anchor arm 26 which is threaded diametrically into and extends radially from the eccentric shaft 16. The said spring anchor arm 26 is preferably cylindrical in shape and is disposed in a semi-circular slot 45 in the main shaft 17 as shown in Figs. 2 and 5. The other end of the said torsional pump

pressure regulating spring 25 is hooked and beveled at 49 to engage the axially angular face 50 of the pump pressure regulating spring adjustment collar 27.

The said pump pressure regulating spring adjustment collar 27 is fixed to the main shaft 17 by a suitable adjustment pin 51 which extends through one of the radially disposed adjustment pin apertures 52 in circumferentially spaced relationship around the said collar 27 and into one of the radially disposed adjustment pin bores 53 circumferentially spaced around the periphery of the said main shaft 17.

The pressure against which the pump delivers a maximum volume of fluid is regulated by the torsional adjustment of the pump pressure regulating spring 25 which is accomplished by first removing the spring adjustment cover plate 54 secured over a suitable rectangular aperture 55 in the housing 22 by the socket head screws 56.

A suitable mushroom head lever wrench 57 is then inserted in one of the shouldered wrench apertures 58 as indicated in Fig. 7, the adjustment pin 51 is removed, the collar is turned up or released back as desired until the desired torsional pump pressure regulating spring tension is attained, the adjustment pin 51 is then inserted in any convenient registering adjustment pin aperture 52 in the pressure regulating spring adjustment collar 27 and the radially disposed adjustment pin bores 53 in the main shaft 17, and the cover plate 54 is replaced.

The front of the main pump casting 10 has an opening therein surrounded by an annular collar 59 covered by a cover plate 60 secured to the said collar 59 by suitable socket head studs 61. A gasket 62 disposed between the end face of the said collar 59 and the cover plate 60 prevents lubricant from within the pump preferably maintained at the level indicated by the numeral 63 in Fig. 1 from leaking out therefrom.

The rear end of the housing 22 having the extended 170 of the main shaft 17 extending therefrom is preferably supported on vertical legs 220 formed integral with the base 100 and has a suitably apertured annular closure 64 secured to the end face thereof by means of socket head studs 65. A gasket 66 disposed between the end face of the rear end of the housing 22 and the closure 64 prevents lubricant within the said housing 22 from leaking out therefrom. The said closure 64 is formed with sufficient space therein to accommodate an oil seal 67 which is disposed around the portion 68 of said main shaft 17 as shown in Fig. 5. The said closure 64 also has an inwardly disposed annular collar 69 which is employed to secure the outer race of the ball bearing 21 against a radially inwardly projecting shoulder 70 formed within the said housing 22.

Referring now to Fig. 6, each of the intake and discharge valves 28 and 29 disclosed comprise a valve seat 71 against which a ball valve member 72 is constantly urged by a spring loaded ball valve thrust plunger 73 having a concaved end 74 for engaging the said ball valve member 72 and urging it centrally toward and against the said valve seat 71. The stem portion of the said ball valve thrust plunger 73 is telescoped within a hollow guide member 75 having a flanged head 76 integral therewith which is threaded in the outer end of the housing of the valve 28 or 29, as the case may be, against a shoulder 77. Socket head plugs 36 and the washers 37 serve as means for locking the flanged

head 76 of the hollow valve stem guide member 75 in position and to assure a pressure-tight seal at the outer end of the housing castings of the said valves 28 and 29 respectively. The said hollow valve stem guide member 75 has a compression spring 78 positioned thereover which reacts against the bottom of the flanged head 76 thereof and engages the bottom of the concaved end 74 of the ball valve thrust plunger 73 for constantly urging the ball valve member 72 against its valve seat 71. Although the foregoing valve mechanism is preferred, obviously, many other types of valve means may be employed.

For example, assume that a pump is constructed in accordance with the instant invention having four cylinders and a maximum piston stroke at low pressure of 1", and, employing a 3 horsepower motor at 1200 R. P. M., the said pump will deliver 9 gallons per minute when the pressure against which it operates is 1666# or less. If the said pump is constructed so that its minimum piston stroke is .333", then, as the pressure against which it operates is increased above 1666# up to 5000#, its eccentric shaft 16 turns within the main shaft 17 so that the center B of the master wrist pin 15 thereof travels from its position of maximum eccentricity with respect to the center A of the main shaft 17 along the path indicated by the dot and dash line 80 shown in Figs. 1 and 5 until the said center B of the master wrist pin 15 arrives at the point C of minimum eccentricity with respect to said main shaft 17. As the eccentricity of the wrist pin 15 with respect to the main shaft 17 becomes reduced responsive to an increase of pressure against which the pump operates, the length of the stroke of the pistons 12 becomes reduced, and the volume delivered by the pump is reduced from the maximum of 9 gallons per minute at a pressure of 1666# to a minimum of 3 gallons per minute at a pressure of 5000#. Conversely, as the pressure against which the pump operates decreases, the length of the stroke of its pistons 12 increase which increases the volume of fluid delivered thereby.

In any one design of pump, the maximum and minimum pressure responsive to which the volume of fluid delivered by the pump varies may be regulated by adjusting the torsional resistance of the pump pressure regulating spring 25 as hereinbefore described in detail. Also, the operating pressures responsive to which the volume of fluid delivered changes automatically may be changed radically over a rather wide range in any pump embodying the invention by merely changing the pump pressure regulating spring 25 to a weaker or a stronger one, all according to the operating pressures desired. Thus one design of pump may be applied to a wide range of uses and requirements.

The invention has been described herein as a pump, however, it is obvious that the invention is also usable as a compressor for compressing air, gases and the like, and, it is intended that the specification and claims herein be construed accordingly.

Although but one illustrative embodiment of the invention has been disclosed and described in detail, it is obvious that many changes may be made in the size, shape, arrangement and detail of the various elements of the invention without departing from the spirit and scope of the invention as defined by the appended claims.

I claim:

1. A pump or compressor comprising a plurality of radially disposed cylinders, a piston reciprocatingly mounted in each cylinder, a drive shaft and an eccentric shaft turnable within the said drive shaft when the said drive shaft rotates, a master wrist pin on said eccentric shaft eccentric to the center thereof and to the center of the said drive shaft, resilient means constantly urging said eccentric shaft to turn with respect to said drive shaft and move said master wrist pin to a position of maximum eccentricity with respect to said drive shaft, the said resilient means permitting the said eccentric shaft to turn to a position wherein the said master wrist pin assumes a position of less eccentricity with respect to the said drive shaft responsive to pressure against which the pump operates.

2. A pump or compressor comprising a plurality of radially disposed cylinders, a piston reciprocatingly mounted in each cylinder, a drive shaft and an eccentric shaft turnable within the said drive shaft when the said drive shaft rotates, a master wrist pin on said eccentric shaft eccentric to the center thereof and to the center of the said drive shaft, a torsional spring connected at one end to the said drive shaft and at the other end to the eccentric shaft constantly urging said eccentric shaft to turn with respect to said drive shaft and move said master wrist pin to a position of maximum eccentricity with respect to said drive shaft, the said torsional spring permitting the said eccentric shaft to turn to a position wherein the said master wrist pin assumes a position of less eccentricity with respect to the said drive shaft responsive to torque developed by the pressure against which the pump operates.

3. A pump or compressor comprising a plurality of radially disposed cylinders, a piston reciprocatingly mounted in each cylinder, a drive shaft and an eccentric shaft turnable within the said drive shaft when the said drive shaft rotates, a master wrist pin on said eccentric shaft eccentric to the center thereof and to the center of the said drive shaft, resilient means constantly urging said eccentric shaft to turn with respect to said drive shaft and move said master wrist pin to a position of maximum eccentricity with respect to said drive shaft, the said resilient means permitting the said eccentric shaft to turn to a position wherein the said master wrist pin assumes a position of less eccentricity with respect to the said drive shaft responsive to pressure against which the pump operates, and means for adjusting the resiliency of the said resilient means whereby to vary the pump pressure responsive to which the said eccentricity of the master wrist pin becomes reduced.

4. A pump or compressor comprising a plurality of radially disposed cylinders, a piston reciprocatingly mounted in each cylinder, a drive shaft and an eccentric shaft turnable within the said drive shaft when the said drive shaft rotates, a master wrist pin on said eccentric shaft eccentric to the center thereof and to the center of the said drive shaft, a torsional spring connected at one end to the drive shaft and at the other end to the eccentric shaft constantly urging said eccentric shaft to turn with respect to said drive shaft and move said master wrist pin to a position of maximum eccentricity with respect to said drive shaft, the said torsional spring permitting the said eccentric shaft to turn to a position wherein the said master wrist pin assumes a position of less eccentricity with respect to the said drive shaft

responsive to torque developed by the pressure against which the pump operates, and means for adjusting the resiliency of the said torsional spring whereby to vary the pump pressure responsive to which the said eccentricity of the master wrist pin becomes reduced.

5. A pump or compressor comprising a plurality of radially disposed cylinders, a piston reciprocatingly mounted in each cylinder, a drive shaft, an eccentric shaft turnable within said drive shaft when said drive shaft rotates, a master wrist pin extending from said eccentric shaft eccentric to the center thereof and to the center of the said drive shaft, the eccentricity of the master wrist pin with respect to the center of the said drive shaft changing as the eccentric shaft turns with respect to the said drive shaft, means connecting the said pistons to the said master wrist pin, and resilient means connecting said eccentric shaft to said drive shaft constantly urging the eccentric shaft to turn with respect to the drive shaft to a position of maximum eccentricity of the said master wrist pin with respect to the said drive shaft, said resilient means permitting the said eccentric shaft to turn responsive to the pressure against which the pump operates to a position of less eccentricity of the said master wrist pin with respect to the said main shaft whereby to automatically vary the volume delivered by the said pump responsive to the pressure against which it operates.

6. A pump or compressor comprising a plurality of radially disposed cylinders, a piston reciprocatingly mounted in each cylinder, a drive shaft, an eccentric shaft turnable within said drive shaft when said drive shaft rotates, a master wrist pin extending from said eccentric shaft eccentric to the center thereof and to the center of the said drive shaft, the eccentricity of the master wrist pin with respect to the center of the said drive shaft changing as the eccentric shaft turns with respect to the said drive shaft, means connecting the said pistons to the said master wrist pin, and a torsional spring connecting said eccentric shaft to said drive shaft constantly urging the eccentric shaft to turn with respect to the drive shaft to a position of maximum eccentricity of the said master wrist pin with respect to the said drive shaft, said torsional spring permitting the said eccentric shaft to turn responsive to the pressure against which the pump operates to a position of less eccentricity of the said master wrist pin with respect to the said main shaft whereby to automatically vary the volume delivered by the said pump responsive to the pressure against which it operates.

7. A pump or compressor comprising a plurality of radially disposed cylinders, a piston reciprocatingly mounted in each cylinder, a drive shaft, an eccentric shaft turnable within said drive shaft when said drive shaft rotates, a master wrist pin extending from said eccentric shaft eccentric to the center thereof and to the center of the said drive shaft, the eccentricity of the master wrist pin with respect to the center of the said drive shaft changing as the eccentric shaft turns with respect to the said drive shaft, means connecting the said pistons to the said master wrist pin, resilient means connecting said eccentric shaft to said drive shaft constantly urging the eccentric shaft to turn with respect to the drive shaft to a position of maximum eccentricity of the said master wrist pin with respect to the said drive shaft, said resilient means permitting the said eccentric shaft to turn responsive to the pressure against which the pump operates to a position of less eccentricity of the said master wrist pin with respect to the said main shaft whereby to automatically vary the volume delivered by the said pump responsive to the pressure against which it operates.

pressure against which the pump operates to a position of less eccentricity of the said master wrist pin with respect to the said main shaft whereby to automatically vary the volume delivered by the said pump responsive to the pressure against which it operates, and means for adjusting the said resilient means to regulate the pressure responsive to which the volume delivered by the said pump automatically reduces.

8. A pump or compressor comprising a plurality of radially disposed cylinders, a piston reciprocatingly mounted in each cylinder, a drive shaft, an eccentric shaft turnable within said drive shaft when said drive shaft rotates, a master wrist pin extending from said eccentric shaft eccentric to the center thereof and to the center of the said drive shaft, the eccentricity of the master wrist pin with respect to the center of the said drive shaft changing as the eccentric shaft turns with respect to the said drive shaft, means connecting said pistons to the said master wrist pin, a torsional spring connecting the said eccentric shaft to said drive shaft constantly urging the eccentric shaft to turn with respect to the drive shaft to a position of maximum eccentricity of the said master wrist pin with respect to the said drive shaft, said torsional spring permitting the said eccentric shaft to turn responsive to the pressure against which the pump operates to a position of less eccentricity of the said master wrist pin with respect to the said main shaft whereby to automatically vary the volume delivered by the said pump responsive to torque developed by the pressure against which it operates, and means for adjusting the said torsional spring to regulate the pressure responsive to which the volume delivered by the said pump automatically reduces.

9. A pump or compressor comprising a plurality of radially disposed cylinders, a piston reciprocatingly mounted in each cylinder, a rotating shaft and an eccentric carried by said rotating shaft turnable with respect to the said rotating shaft during the rotation thereof to positions of more or less eccentricity with respect thereto, said pistons being connected to said eccentric, torsional spring means carried by said rotating shaft constantly urging said eccentric to turn with respect to said rotating shaft to a position of maximum eccentricity with respect thereto, the said torsional spring means permitting the said eccentric to turn to a position of less than maximum eccentricity with respect to the said rotating shaft responsive to pressure against which the pump operates.

10. A pump or compressor comprising a plurality of radially disposed cylinders, a piston reciprocatingly mounted in each cylinder, a rotating shaft and an eccentric carried by said rotating shaft turnable with respect to the said rotating shaft during the rotation thereof to positions of more or less eccentricity with respect thereto, said pistons being connected to said eccentric, resilient means constantly urging said eccentric to turn with respect to said rotating shaft to a position of maximum eccentricity with respect thereto, the said resilient means permitting the said eccentric to turn to a position of less than maximum eccentricity with respect to the said rotating shaft responsive to pressure against which the pump operates, and means for adjusting the resiliency of the said resilient means whereby to vary the pump pressure responsive to which the said eccentricity of the said eccentric becomes reduced.

11. In a pump or compressor, a plurality of radially disposed cylinders, a piston reciprocatingly mounted in each cylinder, a rotating shaft, means carried by and eccentric to said rotating shaft connected to said pistons for reciprocating the same, said eccentric means being turnable to positions of more or less eccentricity with respect to said rotating shaft, resilient means normally urging said eccentric means to a position of maximum eccentricity with respect to said rotating shaft causing said pistons to reciprocate at their maximum stroke, said eccentric means being turnable responsive to torque developed between said rotating shaft and said eccentric means whereby to reduce the stroke at which said pistons reciprocate proportionately to the pressure against which said pump operates.
12. In a pump or compressor, a plurality of radially disposed cylinders, a piston reciprocatingly mounted in each cylinder, a rotating shaft, means carried by and eccentric to said rotating shaft connected to said pistons for reciprocating the same, said eccentric means being turnable to positions of more or less eccentricity with respect to said rotating shaft, resilient means normally urging said eccentric means to a position of maximum eccentricity with respect to said rotating shaft causing said pistons to reciprocate at their maximum stroke, said eccentric means being turnable responsive to torque developed between said rotating shaft and said eccentric means whereby to reduce the stroke at which said pistons reciprocate proportionately to the pressure against which said pump operates, and means for adjusting the resiliency of the said resilient means whereby to vary the torque responsive to which the stroke of the said pistons becomes reduced.

13. In a pump or compressor, a plurality of radially disposed cylinders, a piston reciprocatingly mounted in each cylinder, a rotating shaft, eccentric means rotatable with said rotating shaft connected to said pistons for reciprocating said pistons, said eccentric means being turnable with respect to said rotating shaft to positions of more or less eccentricity with respect thereto whereby to vary the stroke of said pistons, spring means urging said eccentric means to a position of maximum eccentricity, said spring means being movable responsive to torque developed between said eccentric means and said rotating shaft to admit of the reduction of the eccentricity of the said eccentric means with respect to the said rotating shaft.
14. In a pump or compressor, a plurality of radially disposed cylinders, a piston reciprocatingly mounted in each cylinder, a rotating shaft, eccentric means rotatable with said rotating shaft connected to said pistons for reciprocating said pistons, said eccentric means being turnable with respect to said rotating shaft to positions of more or less eccentricity with respect thereto whereby to vary the stroke of said pistons, spring means urging said eccentric means to a position of maximum eccentricity, said spring means being movable responsive to torque developed between said eccentric means and said rotating shaft to admit of the reduction of the eccentricity of the said eccentric means with respect to the said rotating shaft, and means for adjusting the resiliency of the said spring means whereby to vary the torque responsive to which the stroke of the said pistons becomes reduced.
